UNITED STATES PATENT OFFICE.

HARRY J. MACDONALD, OF CHICAGO, ILLINOIS.

FEEDING MECHANISM FOR BUTTON-ATTACHING MACHINES.

1,191,807.

Specification of Letters Patent. Patented July 18, 1916.

Original application filed April 3, 1914, Serial No. 829,270. Divided and this application filed January 2, 1915. Serial No. 22.

To all whom it may concern:

Be it known that I, HARRY J. MACDONALD, a citizen of the United States, and residing at Chicago, Cook county, Illinois, have invented certain new and useful Improvements in Feeding Mechanism for Button-Attaching Machines, of which the following, taken in connection with the drawings, is a description.

10 This invention relates to improvements in feeding mechanism for button attaching machines of the type used for securing hollow shank buttons such as shoe buttons or the like to any kind of flat material.

15 This is a division of my application filed in the United States Patent Office on April 3, 1914, said application bearing Serial No. 829,270.

20 The principal object of my invention is to provide a mechanism whereby buttons of different sizes may be used, such for instance as a large size adapted for use on men's shoes, and a small size suitable for children's shoes, so arranged that each button receptacle may be adjusted to feed the buttons desired into a chute leading to the attaching mechanism.

25 Additional objects and advantages will be apparent from the following description and from the drawings in which,

Figure 1 is a side elevation of the feeding mechanism mounted upon a button attaching machine; Fig. 2 is an elevation of the button containing receptacles of different sizes; Fig. 3 is a vertical sectional view through the center of one of the hoppers or receptacles; Fig. 4 is an enlarged detail of the discharge groove from one of the hoppers and its connection with the feeding chute; Fig. 5 is a top plan view of the button feeding chute; Fig. 6 is a transverse sectional view taken on line 6-6 of Fig. 2, looking in the direction of the arrows; Fig. 7 is a sectional detail of the universal joint connecting the receptacle operating mechanism with the driving mechanism; Fig. 8 is a bottom plan view of a revoluble plate in the hopper; and Fig. 9 is a sectional view through said plate.

30 Referring to the drawings, A represents a suitable table or support upon which the operating mechanism is mounted.

A' is a downwardly inclined frame to which is secured the feeding and attaching mechanism of my machine.

B is a vertical shaft which preferably extends to the floor, and is connected with a foot treadle, or any other suitable motive power, not here shown. Secured to the shaft B is a sprocket chain B' which connects with the operative parts of the button attaching mechanism which is the subject of my pending application.

C² is a shaft which connects with the button attaching mechanism and extends downwardly through the frame A' and has mounted thereon a coiled spring C³, against the tension of which the attaching mechanism is operated.

D is an anvil which is secured to the front of the frame A', and against which the staple forming the button fastener is pressed to secure it in place.

35 Supported above the bed plate A² in a downwardly inclined position is the button feed chute E. This chute is secured in place by the bracket E' rising from the bed plate A², and extends from the button receptacles to the staple forming mechanism.

E² is a rocker arm fulcrumed at E³ to the bracket attached to the bed plate A². One end of this rocker arm is provided with a rectangular slot e into which projects the pin e' by means of which the rocker arm is moved to deliver the button from the feed chute E, that is to be operated upon.

40 F is a button feed arm pivotally secured at one end to the rocker arm E². This button feed arm terminates at the free end thereof in a presser foot e² which engages the button when it reaches the lower end of the feed chute. As will be observed the contour of the end side of the presser foot is concave to adapt it more readily to engage the convex or spherical shape of the top of the ordinary shoe button. A coiled spring c surrounds the shaft E³ upon which the arm E² is rocked and exerts a downward tension upon the upper end of said arm. Secured to the button feed arm F and to the pin e' upon the rocker arm is a coiled spring exerting a downward tension upon the button feed arm F.

45 G is a flexible bearing supported upon the shaft G' on the frame A'. This bearing is provided with a socket g in the upper end thereof and supported therein is a universal joint g' upon which is supported the hopper from which the buttons are to be fed.

50 H is a hopper supporting post rising from

the rear of the supporting frame A', and carried thereon is a revoluble table H'. This table is secured against revolution by the screw H² which engages the post H and supports the table. By this means the hopper is securely locked. Arranged upon the revoluble table H' is a plurality of hoppers h, h', h², of different sizes and adapted to contain different sized buttons. With the exception of the size these hoppers are exactly alike, so that a description of one will suffice for all. The hoppers h, h', h², are preferably cylindrical in form and extending from each one is a hopper base button outlet J adapted to engage the upper end of the button chute E when the hopper is turned to feeding position by revolving the table or hopper base H'. Each of the hoppers is provided with a removable cover i, i', i². Inside of each of said hoppers is a plate or disk K⁵ provided with an opening k, k', k², respectively, said opening graduating in size to allow different sized buttons to pass therethrough on the way to the button chute as they are to be used. The plate K⁵ is fixedly secured to an agitator shaft K' extending through the center of each hopper from the bottom to the top thereof, Fig. 3.

h³ is a small leaf spring secured to the under side of each plate K⁵, which projects into the path of the buttons as they fall into the grooves k⁴. The bottom L of each of the hoppers h, h', h², is supported upon the shaft K' and has an upturned flange l near the periphery thereof, Fig. 3.

Each of the plates L' is provided with a plurality of radially extending sockets in each of which is seated a coiled spring n. An agitator block n' beveled at the outer end thereof is seated in each of said sockets and bears against its corresponding spring n. These blocks extend slightly beyond the periphery of the plate L' into the groove k⁴. The groove k⁴ in each of the button hoppers terminates coincidently with a corresponding groove n² leading to the button outlet J, thence to the chute E.

When the machine is ready for operation the hoppers h, h', h², are filled with buttons of different sizes, preferably of the kind illustrated in Fig. 4 having a spherical head N and loop shank N'. Then after loosening the screw H² which secures the hopper base to its support, the hopper containing the buttons to be used is turned to operative position so that its discharge chute is in line with the groove e³ of the button chute E, and enough buttons are discharged in the chute to fill it as shown in Fig. 4. When it is desired to use buttons of a different size, or kind, in one of the other hoppers, the screw H² is loosened, and the chute E is emptied of the buttons contained therein, the hopper base H' is revolved to bring into po-

sition the receptacle containing the buttons to be used, the screw H² is tightened and the buttons are fed into the chute as before.

To start the buttons feeding through the chute in advance of the operation of the machine, a revoluble crank O is provided which engages either of the agitator shafts K' for the purpose of displacing the buttons in the hopper and causing them to drop through the opening k² in the disk k⁵ onto the plate L', which as previously described, is of smaller diameter than the cylinder forming the hopper thereof, providing a groove between the periphery of the plate L' and the wall of the hopper on a flange l at the bottom thereof.

Through the connection of the universal joint G between the hopper being operated and the operative mechanism of the machine, the agitation of the hopper causes the buttons to drop into the groove k⁴, from whence they are carried toward the discharge groove n² by the motion transmitted to the plate L' with each action of the operative mechanism. With each operation of the machine, attaching a button, the plate L', carrying with it the blocks n' which project across the groove k⁴, moves with them the buttons in said groove to carry them toward the exit J. When the buttons reach the exit from the hopper they drop by gravity into and down the button chute E, where they are delivered by the presser foot F to the operative mechanism as each button is required for attaching. When the button chute is filled, the agitator blocks n' carry the buttons in the groove k⁴ against an obstruction n³ over which they are thrown to the opposite side when they can fall into the groove k⁴ and are carried to the point of exit. As the buttons are used out of the chute more buttons are fed therein from the groove k⁴, so that the button chute is kept full of buttons and ready for operation at any time.

It will be observed that the blocks n' are beveled on the outer end thereof in the direction the buttons are traveling. If the buttons are properly seated with the shanks thereof in the groove k⁴, the pressure of the blocks against them will be sufficient to move them to the point of exit. If, however, any of the buttons are not properly seated in the groove or for any reason are not moving in the direction desired, the small leaf spring h³ secured to the bottom of the plate K⁵ meets said buttons just in advance of the exit and forces them back onto the plate. By the agitation caused with each operation of the machine, the buttons will find their way with the shanks thereof downward into the groove k⁴ ready for exit.

I claim:

1. In a button feeding mechanism, the combination of a revoluble table, a plurality

of receptacles mounted thereon and carried thereby, a guide-way extending from the bottom of each of said receptacles, a downwardly inclined button chute adapted to 5 register with the guide-way of each receptacle as it is brought into feeding position, and a mechanism for directing the movement of the buttons from the receptacles to the button chute, substantially as described.

10 2. In a button feeding mechanism, the combination of a revoluble table, a plurality of button receptacles of different sizes mounted thereon, a guide-way extending from the bottom of each of said receptacles, 15 a downwardly inclined button chute registering with the guide-way of each receptacle as it is turned to feeding position, an agitator shaft extending vertically through each of said receptacles, driving mechanism 20 having connection with said agitator shaft, and means for regulating the advance of the buttons through the receptacle, substantially as described.

25 3. In a button feeding mechanism, the combination of a revoluble table, a plurality of button receptacles of different sizes mounted thereon, an agitator shaft extending vertically through each of said receptacles, a disk fixedly secured to the agitator 30 shaft near the bottom of each receptacle, each disk having an opening of the proper size to permit a single button to drop therethrough, and means for regulating the advance of the buttons through the receptacle, 35 substantially as described.

40 4. In a button attaching machine, the combination of a supporting frame, a driving shaft, a revoluble table, a plurality of hoppers supported thereon, each of said hoppers having a circumferential groove in the bottom thereof extending to the discharge opening, a disk in each of said hoppers upon which the buttons are supported, 45 said disk having an opening therethrough through which the buttons are fed into the aforesaid groove, and means connected with the driving mechanism for agitating the buttons in the hopper with each operation of the machine, substantially as described.

50 5. In a button attaching machine, the combination of a supporting frame, a driv-

ing shaft, a revoluble table, a plurality of hoppers supported thereon, an agitator shaft in each of said hoppers, a revoluble disk in the bottom of each hopper, spring pressed 55 agitator blocks carried with said disk, a disk mounted upon the agitator shaft above the revoluble disk, said disk having an opening through which the buttons fall upon the revoluble disk, and means for directing 60 said buttons to the exit opening, substantially as described.

6. In a button attaching machine, the combination of a supporting frame, a driving shaft, a revoluble shaft, a revoluble table, 65 a plurality of hoppers supported thereon, an agitator shaft in each of said hoppers, a revoluble disk in the bottom of each hopper, said disk being of smaller diameter than the hopper whereby a circumferential groove 70 is formed in the bottom of the hopper, a plurality of agitator blocks carried by said disk and projecting across the groove, a disk supporting the buttons to be used, said disk provided with an opening through which 75 the buttons are dropped onto the revoluble disk, and mechanism connected with the aforesaid driving shaft for agitating said buttons and directing the same toward the point of delivery, substantially as described. 80

7. In a button attaching machine, the combination of a supporting frame, a driving shaft, a revoluble table, a plurality of hoppers supported thereon, an agitator shaft in each of said hoppers, a revoluble disk in 85 the bottom of each hopper, said disk being of smaller diameter than the hopper whereby a circumferential groove is formed in the bottom of the hopper leading to the point of discharge, means for directing the but- 90 tons into said groove and carrying them to the point of exit, and means for retarding the progress of said buttons at predetermined intervals, substantially as described.

In testimony whereof I have signed this 95 specification in the presence of two subscribing witnesses.

HARRY J. MACDONALD.
